UNITED STATES PATENT OFFICE.

JOHN J. TOKHEIM, OF CEDAR RAPIDS, IOWA, ASSIGNOR TO THE TOKHEIM MANUFACTURING CO., OF CEDAR RAPIDS, IOWA.

SELF-MEASURING PUMP.

No. 907,653.

Specification of Letters Patent.

Patented Dec. 22, 1908.

Application filed May 29, 1907. Serial No. 376,324.

To all whom it may concern:

Be it known that I, JOHN J. TOKHEIM, a citizen of the United States, residing at Cedar Rapids, in the county of Linn and State of Iowa, have invented a new and useful Self-Measuring Pump, of which the following is a specification.

This invention relates to self measuring pumps.

The apparatus to which this invention belongs is of that class employed in dispensing mechanically measured quantities of gasoline for use in connection with automobiles and for other purposes. The objections generally present in an organized system of this character are that owing to the presence of dirt, sediment and other extraneous matter in the gasoline, which accumulate in the storage tank and are drawn into the pump and settle on the valve seats, it is practically impossible to maintain a constant priming in the pump, an incident that frequently results in troublesome and annoying delays to the prospective purchaser; that no provision is made to prevent such contingency or to allow easy and rapid restoration of the valves to proper action and the ready removal of extraneous matter from the pump; that the venting of the dispensing reservoir is not sufficiently delicate; and that no adequate arrangement is employed to return all of the unused gasoline to the storage tank without the escape of fumes. Of course it is known that means for obviating two of the above objections are to be found in separate apparatus, as for example, in the patent granted to myself and E. O. Mansfield for a measuring pump, dated February 17, 1903, and numbered 720,638, in which there is shown an apparatus embodying means for mechanically measuring definite quantities of gasoline and for returning the unused portion to the storage tank; but this appliance is lacking in any means for maintaining a positive priming under all conditions of use and for preventing passage of extraneous matter to the pump. Again, in a patent granted to myself for an oil tank, dated July 24, 1906, and numbered 826,912, there is shown an apparatus embodying means for precluding entrance of extraneous matter to the pump and also means for returning all of the unused gasoline to the storage tank; but this appliance is lacking in the means for maintaining a constant priming in the pump cylinder.

The object of the present invention is, therefore in a simple, practical and positive manner and in a single apparatus, to provide means to maintain constant priming, to preclude entrance of extraneous matter to the pump, to effect saving of all of the unused gasoline, to secure novel venting of the dispensing reservoir, and to permit the ready removal of matter drawn from the storage tank to the pump without interfering with the valves of the latter.

With the above and other objects in view, as will appear as the nature of the invention is better understood, the same consists in the novel construction and combination of parts of a combined priming chamber and sediment trap for pumps, as will be hereinafter fully described and claimed.

In the accompanying drawings forming a part of this specification and in which like characters of reference indicate corresponding parts;—the figure represents a longitudinal sectional view of a combined priming chamber and sediment trap constructed in accordance with my invention.

Referring to the drawings 8 indicates the combined priming chamber and sediment trap having a pipe 9 communicating with the interior of the trap at the upper end thereof and leading to a tank or other source of gasoline supply (not shown). In addition to performing the function of a priming chamber and sediment trap, the member 8 also forms the lower cap for the pump cylinder 10 which may be of the usual or any preferred construction and carries at its upper end a cap 11 with which is connected the outlet pipe 12.

If desired, a plurality of pipes 9 may be connected with the trap so one pump may draw gasoline from a number of tanks by providing the different pipes with valves 9^a to close or open them.

The trap is provided near its upper end with a partition 13 that is centrally orificed and threaded to receive the external threads of a sleeve 14, the interior of which is threaded and is engaged by an inlet pipe 15 that extends to a point near the bottom of the trap and carries a screen 16. This pipe 15 is provided near its upper end or adjacent to the partition 13 with a non-siphoning orifice 16^a, which, as will appear later on operates positively to prevent the trap from being emptied of gasoline, whereby a constant sup-

ply for priming is always present. Moreover, this non-siphoning orifice is of such a diameter as not to interfere with the operation of the pump on its first upward stroke, 5 to cause a priming charge to pass to the pump cylinder.

The lower end of the trap is provided with a threaded orifice that is engaged by a clean-out plug 17, the object of which is to permit 10 the removal of any accumulation of extraneous matter in the trap which might operate to interfere with the proper action of the pump.

The term "sediment" is herein employed 15 generically to include dirt or foreign matter of any character present in the gasoline that will tend to clog the pump valves or otherwise detract from the proper operation of the apparatus.

20 The periphery of the upper portion of the sleeve 14 is threaded and engaged by an annulus 18 forming the base of the cage 19 that is operated to hold in proper position a weighted valve 20 that normally closes the 25 upper end of the inlet pipe 15. This valve is provided with an arm 20^a that extends slightly above the upper face of the cage and is designed to be engaged by the lower face of the piston 21 with which is connected a pump 30 rod 22 of any approved construction.

The piston embodies a six armed cage 23, with which the pump rod is connected and which serves to house an upwardly opening valve 24 that is provided with a downwardly 35 projected boss or teat 25 designed to engage a stud or lug 26 on the upper face of the valve 20.

The object of the arm 20^a and extension 25 is to cause the unseating of the two valves, 40 whereby that gasoline remaining in the pump cylinder and pipes after the pump has been operated to elevate the charge will be permitted to pass back through the trap and thus leave the priming for a succeeding oper- 45 ation.

In the operation of the device, when the

pump rod is actuated by means of an ordinary handle, (not shown) on the first up-stroke of the piston the gasoline will be drawn from the trap through the inlet pipe 50 15 into the lower portion of the pump cylinder and thence through the outlet pipe 12. If during the operation of the pump any extraneous matter be drawn through the pipes 55 9 into the trap it will be prevented by the strainer 16 from entering the inlet pipe, and after a period, which may be determined by observation or otherwise, the plug 17 will be removed and the sediment cleaned from the cap. At the conclusion of the pumping operation, when the piston is moved downward the valves 20 and 24 will be tripped by the mechanism described and the gasoline in the pumping system will pass back into the tank through the cylinder 10, the primer 8 and 60 pipe 9, but as soon as the level of the gasoline passes below the opening 16^a any siphoning action will be precluded so that there will always be sufficient gasoline or liquid within the trap to insure the proper priming of the 70 pump.

What is claimed is:—

The combination with a pump, of a combined priming chamber and sediment trap provided at its lower end with a clean out 75 plug, a partition secured within the trap near its upper end, a pipe depending from the partition and provided near its upper end with non-siphoning opening and at its lower end with a screen, a trip valve supported by the 80 partition and arranged over the upper end of the pipe for controlling passage therethrough, and a supply pipe discharging into the trap below the non-siphoning opening.

In testimony that I claim the foregoing as 85 my own, I have hereto affixed my signature in the presence of two witnesses.

JOHN J. TOKHEIM.
